ATTORNEY

UNITED STATES PATENT OFFICE.

SAMUEL T. HAVILAND, OF JAMISON, ALABAMA.

LOG-TURNER.

SPECIFICATION forming part of Letters Patent No. 295,549, dated March 25, 1884.

Application filed July 13, 1883. (No model.)

To all whom it may concern:

Be it known that I, SAMUEL T. HAVILAND, a citizen of the United States, residing at Jamison, in the county of Chilton and State of Alabama, have invented certain new and useful Improvements in Log-Turning Machines, of which the following is a specification, reference being had therein to the accompanying drawings.

10 This invention relates to improvements in turning logs in saw-mills, and has for its object to facilitate this operation by means of simple and inexpensive machinery. This object is attained by the mechanism illustrated 15 in the accompanying drawings, in which—

Figure 1 is a side elevation. Fig. 2 is a transverse section. Fig. 3 is a detailed view of some of the parts removed. Fig. 4 is a plan.

The letter E represents a platform, or it may 20 form a portion of the floor of the mill, upon which it is placed and firmly secured thereto. The frames or timbers F' F are kept a small distance apart by the intervening pieces, F', and the whole of which are fastened together by 25 the bolts H. The frames F and F' are placed a convenient distance apart, and form bearings for a shaft, G, to which are securely attached arms B B', and also a handle or lever, D. The arms B B', when in a horizontal position, 30 lie, respectively, between the timbers F' F and F F', and are concealed from view. They are provided at their extremities with notches b b', which fit over the V-shaped portion a of the arms A. The arms A are of an elbow shape 35 at one end, and are suspended between the timbers F F' by the pivots a", upon which they turn. When in a horizontal position, their upper edges are on a line with the upper part of the beams F F', and when in this position and 40 it is desired to turn a log, the handle D is raised to a vertical line. This causes the arms

B B' to engage their notches b b' with the V-shaped portion a of the arms A and cause them to rise and bear against the under side of the log and turn it upwardly to such an angle that 45 the operation is easily completed by a cant-hook in the usual manner, as the log is effectually prevented from slipping backward by the arms A. The notches b b' and the V-shape portion of the arms A, over which they 50 fit, form guides and prevent any lateral slipping of the arms B B' in the act of raising the arms A, and by making the arms of elbow shape the pivots a" are placed a good deal below the upper edges of the beams F, and thereby enable the handle D to be raised with very 55 much less power than would be required if the pivots were placed near the tops of the beams F F'.

In addition to gaining more power in having the upper beams in an angular shape, it enables it to throw the log back far enough, so that in turning it over the corner will not hang on the end of head-block.

Having described my invention, what I desire to secure by Letters Patent and to claim is—

In a log turner, the combination of the frames F F', mounted upon a suitable base, the arms A, having an elbow pivoted to said frames and 70 provided with V-shaped slides a, the arms B B', secured to said shaft and having notches b b', and the shaft G, mounted in the said frames and having a handle, D, as described, and for the purposes set forth.

In testimony whereof I affix my signature in presence of two witnesses.

SAMUEL T. HAVILAND.
